UNITED STATES PATENT OFFICE.

JOHN N. ROSE, JR., OF KINSLEY, KANSAS.

INTERNAL-COMBUSTION ENGINE.

1,111,765.

Specification of Letters Patent. Patented Sept. 29, 1914.

Application filed November 19, 1913. Serial No. 801,923.

To all whom it may concern:

Be it known that I, JOHN N. ROSE, Jr., a citizen of the United States, residing at Kinsley, in the county of Edward and State 5 of Kansas, have invented certain new and useful Improvements in Internal-Combustion Engines; and I do hereby declare the following to be a full, clear, and exact description of the invention, such as will enable others skilled in the art to which it ap- 10 pertains to make and use the same.

This invention relates to internal combustion engines of the four cycle type, and one of the principal objects of the invention 15 is to simplify and render more efficient the valve mechanism of engines of the type referred to and to provide an intake and an exhaust valve of the piston type, to be operated by cams on a single shaft.

Another object of the invention is to provide means for constantly feeding oil to the lower portions of the valve casing so that as the piston valve descends a small quantity of oil is taken up and applied to the inner 25 wall of the valve casing while an overflow pipe leads from the bottom of the valve casing to the crank chamber, said overflow pipe also serving to relieve the valve chambers of any excess of air or compression caused by 30 the opening and closing of the valve.

Still another object of the invention is to provide an internal combustion engine, in which the intake and exhaust valves are not exposed to the action of the gases excepting 35 at the surface of the head of the piston where no harm can be done to the operation of the valve.

In engines of the type referred to, the valve mechanism is usually a source of more 40 trouble than any other portion of the engine, owing to the fact that the valves are usually exposed in great part to the action of the gases and this leads to many irregularities in the operation of the valve, which 45 means constant attention.

It is one of the principal objects of this invention to overcome the defects and irregularities referred to by means of valves of the piston type, which are not exposed to the direct 50 action of the gases, excepting the surface of the head of the valve.

These and other objects may be attained by means of the construction illustrated in the accompanying drawings, in which,

55 Figure 1 is a side elevation of an internal combustion engine, made in accordance with

my invention, the lower portion of the crank chamber and oil receptacle, being broken away, Fig. 2 is a vertical sectional view taken through the cylinder, one of the valve casings, and the oil receptacle, and Fig. 3 is a detail sectional view showing the means for operating the oil pump rod, said view being taken on the line 3—3 of Fig. 2, looking in the direction indicated by the arrows. 60

Referring to the drawings the numeral 1 designates the cylinder, 2 is the crank casing, and 3 is the bottom of said casing. The cylinder 1 is provided with a water jacket 4. The piston head 5, the connecting rod 6, 70 the crank portion 7, on the crank shaft 8, may be of the usual or any suitable construction. The valve casing 9 may be formed on or connected to the cylinder 1, and the valve casing communicates with the interior 75 of the cylinder 1 at the top, as indicated at 10.

An inlet pipe 11, from a source of fuel supply, leads into the valve casing 9, while an exhaust pipe 12 also communicates with the 80 valve casing 9 in alignment with the exhaust valve, while the inlet pipe 11 communicates with the valve casing in line with the intake valve.

Since the intake valve and the exhaust 85 valve are identical in construction, and are operated by the same character of mechanism, a description of one of these valves will serve for both.

The intake valve comprises a piston head 90 13, having the usual expansion rings, and a valve stem 14 preferably formed integral with the head 13. The valve stem 14 extending through a guide element 15, secured to the top of the crank chamber 2, 95 said valve stem also extending through the top of said casing and being provided on its lower end with an anti-friction roller 16, is adapted to bear upon a cam 17 mounted on a cam shaft 18, which may be operated 100 or actuated by means of a gear wheel 19 on said shaft which meshes with a smaller gear 20 on the crank shaft 8. A spiral spring 21 encircles the valve stem 13, the upper end of said spring bearing against a 105 boss at the lower end of the valve casing 9, while the lower end of said spring bears against an adjusting collar 22, provided with a set screw 23 for regulating the tension of the spring 21.

The valve casing 9 is provided at its upper 110 end with a removable plug 24, through

which the spark plug 25 extends, while the exhaust valve casing is provided with a similar plug 26.

An oil supply pipe 27 communicates with the lower end of the valve casing 9, as at 28, said pipe extending down to an oil pump 29, disposed within the lower portion of the casing 3. The oil pump 29 may be of any suitable type and as shown is operated by means of the pump rod 30, the upper end of which carries a worm 31 operated by a worm gear 32 on the cam shaft 18, said pump rod extending through a guide bracket 33. The oil pump furnishes a supply of oil 34 in each of the valve casings 9, at a sufficient height so that the valve head 13 dips into it at each downward stroke. An overflow oil pipe 33 communicates with the oil pump in the valve casing 9 at a point which determines the oil line in said pump, the overflow pipe discharging at its lower end 34 within the crank casing 2, and providing a quantity of oil 35 in the rounded bottom 36 of the crank casing. The overflow pipe 33 also serves to relieve the valve casing 9 of undue compression, or vacuum. An oil reservoir 37 is located underneath the crank chamber and a pipe 38 leads from the oil reservoir to the pump cylinder 29. A return pipe 39, having its inlet opening disposed at the oil line within the crank chamber 3, is bent down and communicates with the oil reservoir 37, so that an intake of oil is fed back to the reservoir 37.

As shown in Fig. 1 the overflow pipe 33 is provided with a branch pipe, one end of which communicates with the inlet valve and the other end with the exhaust valve. The exhaust valve stem 14^a is provided with a guide element 15^a and an adjusting ring 22^a, and a spring 21^a, which are substantially identical with the parts already described in relation to the inlet valve, and this exhaust valve is operated by a cam 45 similar to the one already described and properly positioned upon the shaft 18.

The operation of the engine may be briefly described as follows:—When the piston head 5 is at the limit of its upward stroke, the intake valve moves down past the inlet pipe, and as the piston moves down it draws in a charge of gas. As the piston starts upward the intake valve closes and the exhaust valve being also closed, the piston compresses the charge, after which the charge is fired. When the piston moves down on the working stroke both valves remain closed until the piston gets to the bot-

tom of the working stroke and then the exhaust valve comes down past the opening 60 in the exhaust pipe and the said gases pass out, this valve remaining open until the piston gets to the limit of its upward stroke, when it closes and the intake valve is below the opening in the fuel pipe. 65

From the foregoing it will be obvious that the intake and exhaust valves of the piston type, provided with expansion rings and operating in casings having oil pockets below them are practically proof against leakage, and are reliable and noiseless. 70

What is claimed is:—

1. In an engine the combination of a cylinder, a piston therein, a valve casing communicating with said cylinder, piston 75 valves mounted in said casing, one of said valves controlling the intake and the other controlling the exhaust, an oil pump, a pipe leading from said pump to said valve casing, an overflow oil pipe communicating 80 with said casing, and having its discharge end disposed within the crank casing, and means for operating said valve.

2. In an engine and in combination with the cylinder, pistons, and means to operate 85 the same, of a valve casing, said valve casing communicating with said cylinder, a piston valve mounted in said casing and adapted to control the intake of fuel, said valve comprising a piston head, a rigid 90 stem, a roller mounted on the end of said stem, cams for operating said valve, an oil pocket in the casing, an oil pump for feeding oil to the pocket, an overflow pipe communicating with said pocket, said overflow 95 pipe having its discharge end located in the crank casing.

3. In an engine the combination of a cylinder, a piston mounted therein, a valve casing communicating with said cylinder, an 100 inlet valve and an exhaust valve mounted in said casing, an oil pocket for each valve in said casing, an oil pump, a pipe leading from the oil pump to each of said oil pockets, an oil reservoir, an overflow pipe communicating with each of said pockets and discharging into the crank casing of the engine, a return pipe leading from the crank casing to said oil reservoir, and means for operating said valve. 105

In testimony whereof I affix my signature in presence of two witnesses.
